TRIGGER MECHANISM FOR MACHINE GUNS

William R. Bluehdorn, Hartford, Conn., and
Forrest K. Howard, East Falls Church, Va.

Application January 16, 1935, Serial No. 2,028

1 Claim. (Cl. 89—27)

(Granted under the act of March 3, 1883, as
amended April 30, 1928; 370 O. G. 757)

The invention described herein may be manufactured and used by or for the Government for governmental purposes, without the payment to us of any royalty thereon.

5 The subject of this invention is a trigger mechanism for machine guns.

Machine guns mounted on aircraft and adapted to fire between the blades of the propeller are operated by means of a trigger motor attached to 10 the exterior of the gun casing and synchronized with the motor of the aircraft. The same type of gun is also mounted on other parts of the aircraft where synchronized firing is not required and it is also employed in tanks and armored 15 cars. In these instances the gun is manually operated either directly or through remote control.

20 The purpose of this invention is to provide a hand trigger mechanism which may be readily interchanged with a right or left trigger motor without altering the standard equipment of the gun or interfering with its operative parts and which utilizes the attaching means of the trigger motor.

25 A further object is to provide a simple trigger which may be actuated when the gun equipped with the trigger is mounted for recoil and counterrecoil movement.

To these and other ends, the invention consists 30 in the construction, arrangement and combination of elements described hereinafter and pointed out in the claim forming a part of this specification.

35 A practical embodiment of the invention is illustrated in the accompanying drawing, wherein:

Fig. 1 is a view in side elevation of a machine gun equipped with the improved trigger.

Fig. 2 is a transverse sectional view through 40 the breech casing and showing the trigger in cocked position.

Fig. 3 is a similar view with the trigger held in the firing position by a remotely controlled mechanism.

45 Fig. 4 is a sectional view on the line 4—4 of Fig. 3, and

Fig. 5 is a perspective view of the trigger.

Referring to the drawing by characters of reference, there is shown a machine gun of the 50 Browning type whose breech casing consists of spaced side plates 5—5 between which the usual breech bolt 6 is reciprocally mounted. The bolt has a sear 7 for releasably holding a firing pin (not shown) and is moved by a transversely disposed sear slide 8 which is of the type employed in connection with the trigger motors of synchronized guns.

The side plates 5 are each formed with a pair of apertures 9—10 for mounting a trigger motor but in the present instance they are employed to mount a plate 11 of a hand trigger mechanism by means of the conventional front cleat 12 and 5 rear cleat 13 which is associated with a bolt 14 as is well understood in the art.

The plate 11 is formed with a groove 15 for receiving a trigger 16 which is pivotally mounted at its front end on a pin 17 carried by the plate. 10 The trigger is normally held in the cocked position shown in Fig. 2 by means of a spring 18 seated in a recess 19 in the plate and in a recess 20 in the trigger. Outward movement of the trigger is limited by the engagement of its toe 21 15 with the front wall 22 of the groove 15 and inward movement is limited by the floor 23 of the groove.

A lug 24 on the inner side of the trigger extends through an aperture 25 in the plate 11 in 20 position to engage the sear slide 3 when the breech bolt is "in battery". The rear face of the lug is beveled to provide a cam surface 26 which serves, in continuous firing, to actuate the sear slide as the breech bolt approaches the "in 25 battery" position.

The trigger is actuated by direct manual engagement or by remote control as shown in Fig. 3. In the latter instance a plunger 27 is slidably mounted in a bracket 28 attached to the gun 30 cradle 29. The plunger is retracted by means of a cable 30 against the action of a spring 31 which is confined between the bracket and a pin 32 on the plunger. The front end of the plunger is formed with a cam surface 33 for engaging a 35 cam surface 34 on the front face of a lug 36 which is provided on the outer side of the trigger. This arrangement functions to press the trigger even when the trigger is longitudinally displaced as when the machine gun is mounted on a recoil- 40 ing cradle.

We claim:

In a machine gun having a breech casing, a plate attached to the casing and formed with a groove on its outer side, a trigger lever pivotally 45 mounted at its front end in the plate and disposed in the groove of the plate, the front end of the lever engageable with the plate to limit its movement to cocked position, a spring between the plate and lever and normally holding the 50 lever in cocked position, and a sear actuating lug on the inner side of the lever and in rear of the pivot of said lever, said lug extending through the plate and into the gun.

55
